United States Patent Office

Des. 184,338
Patented Feb. 3, 1959

184,338

FREIGHT CAR

Frank E. Cheshire, Evansville, Ind., assignor to International Steel Company, Evansville, Ind., a corporation of Indiana

Application June 13, 1955, Serial No. 36,472

Term of patent 14 years

(Cl. D66—1)

Fig. 1 is a perspective view of a freight car, showing my new design;

Fig. 2 is a top plan view;

Fig. 3 is an end view; and

Fig. 4 is a view of the other end of the freight car of my new design.

The side opposite the side shown in the perspective view of Fig. 1 is similar to the side shown in Fig. 1.

I claim:

The ornamental design for a freight car, as shown and described.
